UNITED STATES PATENT OFFICE.

KOHLER GREENFIELD, OF KERNERSVILLE, NORTH CAROLINA.

RAILROAD TIE.

Application filed December 5, 1923. Serial No. 678,710.

To all whom it may concern:

Be it known that I, KOHLER GREENFIELD, a citizen of the United States, residing at Kernersville, in the county of Forsyth and 5 State of North Carolina, have invented certain new and useful Improvements in Railroad Ties, of which the following is a specification.

My present invention has for its object the 10 provision of a railroad tie of novel construction which will yieldably support the track rails so that the comfort of passengers in trains passing over the road will be enhanced. Another object of the invention is to provide 15 a railroad tie which will be durable and may be easily and rapidly laid in the roadbed, and the invention seeks further to provide a railroad track support having resilient qualities which will, nevertheless, firmly support 20 the rails and the parts of which will not be apt to become separated through customary usage. These stated objects, and other objects which will incidentally hereinafter appear, are attained in such a device as is illustrated 25 in the accompanying drawings, and the invention resides in certain novel features which will be particularly pointed out in the appended claims.

In the drawing:

30 Figure 1 is a perspective view of my improved railroad tie showing a pair of track rails thereon, the rails being in section;

Fig. 2 is a longitudinal section on the line 2—2 of Fig. 1;

35 Fig. 3 is a transverse section on the line 3—3 of Fig. 2;

Fig. 4 is a perspective view of the top plate, and

40 Fig. 5 is a view showing the base and the cap plates in perspective.

In carrying out my invention, I employ a base 1, which is preferably of metal, of suitable dimensions to extend across a roadbed and provided at its top along its sides with 45 vertical flanges or ribs 2. The central portion of the base is recessed, as shown at 3, whereby to provide a chamber which will accommodate the fulcrum or rocker of the top plate, and at the centers of the side portions of the base are notches or openings, indicated at 4, which extend to the top of the same, as will be understood. Extending across the base is a channel 5 which is alined with the lower ends of the notches 4 and accommodates a transverse rib 6 on the under 55 side of the top plate 7, which rib is extended

beyond the sides of the top plate to provide trunnions 8 fitting in the notches 4 of the base so that the top plate may readily rock upon the base. Cap plates 9 are secured to the base at each side of the top plate, and these cap plates rest upon the upper edges of the flanges 2, as shown in Fig. 1, and are further provided with depending webs 10 which bear against the side of the base and are bolted thereto. Midway their ends, the webs 10 are provided with notches 11 adapted to fit over the trunnions 8 and on their inner sides the cap plates are provided with lugs 12 fitting in the upper ends of the notches 4 and bearing upon the trunnions 8 to prevent the same rising so as to be detached from the base. The top plate 7 is provided on its under side with a depending enlargement or body 13 which fits between the sides of the chamber 3 in the base, and the under surface of this enlargement or body is formed on inclined planes converging downwardly from its ends to its center so as to merge into the rocker or rib 6 which is illustrated as an integral part of the top plate. The groove 5 in the base is, of course, concentric with and seats the fulcrum or rib 6 while the ends of the top plate rest upon springs 14 which are disposed at the ends of the base in sockets 15 provided therefor and bear against the under side of the top plate, as shown clearly in Fig. 2. The sockets or recesses 15 will serve to prevent displacement of the springs 14 but bosses 16 may be provided on the under side of the top plate to engage in the upper ends of the springs to aid in centering the same if so desired. In the upper surface of the top plate 7 adjacent the ends thereof, I form transverse grooves 17 in which the base flanges of the rails 18 are received, the said grooves being of such width that they will snugly engage the bases of the rails so that movement of the rails transversely of the track will be prevented, spreading of the rails being thereby avoided and the gage of the road being maintained. To retain the rails upon the top plate 7, I provide the keeper plates 19 which are secured upon the top plate 7 at opposite sides of the rails and have their inner edge portions slightly offset vertically, as shown at 20, whereby they are adapted to fit over the base flanges of the rails. The keeper plates 19 are secured to the top plate 7 by bolts 21 or their equivalents and the inner edges of the said plates

abut the rails so that the rails will be firmly secured upon the top plate of the tie, as will be understood.

From the foregoing description, taken in connection with the accompanying drawings, it will be seen that I have provided an exceedingly simple railroad tie which is strong and durable in construction. The ends of the upper member of the tie will be yieldably supported by the springs 15 but it will be prevented from moving out of place vertically by the caps or keeper plates 9 which engage over the trunnions 8. When a load is imposed upon the track, as by a passing train, the springs 14 will yield slightly to the load so that the load will be sustained but the travel of the train will be cushioned. Should the train or any one car in the train be loaded more heavily upon one side than on the other side, the resilient mounting at the ends of the top plate will permit the said plate to accommodate such inequality of the load to the limit of compression of the spring and contact between the end of the upper member and the end of the base member and will thereby tend to overcome the liability of freight to shift about in the car while the passengers will not be subjected to discomfort or inconvenience. My improved tie is compact and may be produced, assembled and laid at a less cost than less durable ties are now furnished.

It is to be understood that while the drawings show the preferred embodiment of the

invention, I do not limit myself to the precise details illustrated as various minor changes may be made therein without departing from the invention as the same is defined in the following claims.

Having thus described the invention, I claim:

1. A railroad tie comprising a base having a longitudinally extending chamber in its upper side midway its ends, a top plate provided on its under side at its center with a rocker adapted to seat in said chamber, means to engage said rocker and retain the top plate in its operative relation to the base, and yieldable supports upon the base for the ends of the top plate.

2. A railroad tie comprising a base having a longitudinally extending recess in its upper side midway its ends and provided at its center with a transverse groove in the bottom of said recess, a top plate having a depending rocker body on its under side at its center, said rocker body being formed with laterally projecting trunnions at the sides of the top plate to engage in the side portions of the base, yieldable supports carried by the base for the ends of the top plate, and keeper plates secured upon the base and engaging over the said trunnions whereby to retain the top plate upon the base.

In testimony whereof I affix my signature.

KOHLER GREENFIELD. [L.S.]
